[57] **CLAIM**

The ornamental design for a head of a flashlight, as shown and described.

DESCRIPTION

FIG. 1 is a perspective view of a head for a flashlight taken from the front, top and right side thereof showing my new design, the portion shown in phantom is illustrative of a flexible core to which my new design may be attached; FIG. 2 is a right side elevational view thereof; FIG. 3 is a left side elevational view thereof; FIG. 4 is a top plan view thereof; FIG. 5 is a bottom plan view thereof; FIG. 6 is a front elevational view thereof; and, FIG. 7 is a rear elevational view thereof. The broken lines are shown for illustrative purposes only and form no part of the claimed design.

1 Claim, 3 Drawing Sheets
